COMBINED BRAKE BEAM AND BOTTOM ROD SUPPORT

Filed July 20, 1937

Fig. 4. A perspective view of a curved metal component, likely a bracket or support. The component is labeled with various numbers: 11, 8, 12, 13, 14, 15, 16, 17, and 18. Part 11 is a hole on the top surface. Part 8 is a slot or opening. Part 12 is a rib or ledge. Part 13 is a vertical flange. Part 14 is a horizontal flange. Part 15 is a rib or ledge on the side. Part 16 is a slot or opening on the side. Part 17 is a rib or ledge on the bottom. Part 18 is a slot or opening on the bottom. The component is shown in a perspective view, highlighting its three-dimensional structure and various features.

COMBINED BRAKE BEAM AND BOTTOM ROD SUPPORT

Joseph L. Ortner, Cincinnati, Ohio

Application July 20, 1937, Serial No. 154,671

10 Claims. (Cl. 188—210)

This invention relates to safety mechanism for railway cars and more particularly to a combined brake beam and bottom rod support for the brake rigging thereof.

5 The object of the invention is to provide a comparatively simple and inexpensive device of the character described which may be economically stamped, punched or otherwise formed from a single sheet of metal and in which the bottom rod support or stirrup is offset with respect to the vertical plane of the spring board engaging hook so as to provide additional strength at the junction of the stirrup and brake beam supporting arm and consequently prevent accidental bending or 15 breakage of the bracket at the point subjected to the most strain.

A further object of the invention is to provide a safety device including an integral bracket, the bottom rod support or stirrup of which is formed by bending the metal downwardly at opposite sides of the brake beam supporting arm and at 20 a point intermediate the length of said arm whereby the stirrup will be the proper length to support the bottom rod without the necessity of bending the lower end of the stirrup to prevent 25 track interference while at the same time insuring full strength of the metal at the angle of the bracket where the greatest strength is necessary.

A still further object of the invention is generally to improve this class of devices so as to increase their utility, durability and efficiency.

In the accompanying drawing forming a part of this specification and in which similar numerals of reference indicate corresponding parts in 35 all the figures of the drawing:

Figure 1 is a vertical sectional view of a portion of a railway car truck showing the safety device in position thereon,

Figure 2 is a vertical sectional view taken on 40 the line 2—2 of Figure 1,

Figure 3 is a top plan view, and

Figure 4 is a perspective view of one of the complete brackets.

The improved safety device forming the subject-matter of the present invention is principally designed for application to railway car trucks and by way of illustration is shown in connection with a portion of a truck in which 5 designates one of the brake beams, 6 the spring board and 7 the 50 brake rod which extends beneath the spring board in the usual manner.

The device comprises a unitary structure in the form of an integral bracket, two of which are preferably used on each truck and arranged in 55 pairs at opposite sides of the spring board 6, but

a single bracket, however, being shown in the present instance. The bracket is stamped or otherwise formed from a single sheet of metal, one end of which is bent in a vertical plane to form an upstanding portion 8 terminating in a downwardly extending hook 9 adapted to fit over the upper edge of the flange 10 of the spring board, as best shown in Figure 1 of the drawing. Extending laterally from the upstanding portion 8 is a horizontally disposed brake beam supporting arm 11 provided with an upstruck longitudinal reinforcing rib 12 defining side flanges 13, the inner end of the reinforcing rib 12 gradually merging into the upstanding portion 8 to form an inclined brace 14 connecting the upstanding portion 8 and arm 11, as shown. The metal at the outer end of the arm 11 and at the side flanges 13 is cut or severed at 15 and the cut or severed portion of the metal pressed downwardly at a point intermediate the length of the supporting arm 11 to form an integral depending stirrup 15, the opening 16 of which is adapted to receive and support the brake rod 7. By forming the stirrup 16 integral with the arm 11 and extending said stirrup downwardly at right angles to said arm 20 and at a point substantially midway between the opposite ends of the arm, said stirrup will be of the proper length to support the brake rod 7 without the necessity of bending the lower end of the rod bracket laterally to prevent track interference, which bending operation would be necessary if the cut or severed portion forming the stirrup were extended to the angle of the bracket. Moreover, by forming the stirrup in this manner full 25 strength of the metal at the angle between the upstanding portion 8 and horizontal supporting arm 11 is assured and this strength is materially increased owing to the diagonal hollow brace 14 connecting the vertical extension 8 with the arm 11. Furthermore, a saving in metal is effected 30 inasmuch as the lower or closed end of the stirrup is cut directly from the end of the arm 11 and bent downwardly so that it is not necessary to cut or otherwise trim the blank from which the bracket is formed.

The inner walls of the overhanging hook 9 are disposed parallel with each other so as to have a sliding fit with the adjacent walls of the upstanding flange 10 of the spring board and the bill of the hook 9 is made relatively short as this hook 50 merely serves to center and temporarily support the bracket in position on the spring board 6. The upstanding portion 8 of the bracket is provided with one or more openings 17 adapted to receive bolts, rivets or similar fastening devices 18 55

which extend through corresponding openings in the upstanding flange 18 of the spring board and serve to secure the bracket in proper position on the spring board. Owing to the fact that the 5 bill of the hook 9 is relatively short, said hook will not form an obstruction or interference when securing the rivets 18 in position. The bracket is placed in position on a car truck in the manner shown in Figure 1 of the drawing, that is to say, 10 with the hook 9 extending over the vertical flange of the spring board 6 and with the horizontal arm 11 disposed beneath the brake beam 5 and in which position the depending stirrup 15 will support the bottom rod 7, as will be readily understood.

It will thus be seen that there is provided a new article of manufacture embodying an integral or homogeneous structure which can be conveniently and economically stamped from a single 20 length of metal and which will effectually prevent the brake beam and brake rod from falling on the track should either of said parts become broken or fail to function properly, thereby preventing serious accidents which might otherwise occur. Inasmuch as the suspension hook, rod 25 supporting stirrup and horizontal brake beam supporting arm are stamped from a single sheet of metal, a unitary structure is provided, the parts of which coact to support the brake beam and 30 brake rod in case of accident and without the employment of independent elements for this purpose.

Having thus described the invention, what is claimed as new is:

35 1. A safety device for car trucks comprising a bracket having means for attachment to the flange of a spring board and provided with a horizontally disposed brake beam supporting arm, the material constituting opposite side portions 40 of the arm being bent downwardly in spaced relation to ends of the arm to form a rod supporting stirrup depending therefrom at a point intermediate the length thereof.

45 2. A safety device for car trucks comprising a bracket having an upstanding portion terminating in a hook adapted to fit over the flange of a spring board and provided with a horizontally disposed brake beam supporting arm, the material constituting the opposite side of the arm being 50 bent downwardly at a point intermediate the length of said arm to form a rod supporting stirrup, and means for securing the bracket in position on the spring board.

55 3. A safety device for car trucks comprising a bracket having an upstanding portion for engagement with the flange of a spring board and provided with an integral horizontally disposed brake beam supporting arm, said horizontal arm being cut across its front end and along its sides 60 for a portion of its length to provide a U-shaped portion bent downwardly to form a bottom rod supporting stirrup depending from opposite sides of the front end of the uncut rear portion of the horizontal arm and offset with respect to the upstanding portion of said bracket.

70 4. A device of the class described comprising a bracket having an upstanding portion terminating in a depending hook for engagement with the flange of a spring board, a horizontally disposed 75 brake beam supporting arm extending laterally from one side of the upstanding portion and provided with a longitudinal reinforcing rib defining side flanges, the material at the end of the arm and at said side flanges being pressed downwardly

at a point intermediate the length of the arm to form a depending rod supporting stirrup.

5 5. A safety device for car trucks comprising a bracket having an upstanding portion adapted to bear against the adjacent side of the upstanding flange of a spring board and terminating in a depending hook fitting over the top of said flange, there being spaced openings formed in said vertical portion, a horizontal brake beam supporting arm projecting laterally from said upright portion, the material constituting the opposite side portions and front end of the arm being bent downwardly intermediate the length of the arm to provide the arm intermediate its ends with an integral depending rod supporting stirrup, and 10 fastening devices extending through the openings in the upstanding portion of the bracket and engaging the flange of the spring board.

6. A safety device for car trucks comprising a bracket having an upstanding portion terminating in a depending hook for engagement with the vertical flange of a spring board and provided with a horizontally disposed brake beam supporting arm formed with a hollow longitudinal reinforcing rib connecting the upstanding portion of 20 the bracket with said arm, the front end and portions of the arm at opposite sides of the rib being cut to form a U-shaped portion having its arms terminating intermediate the length of the brake beam supporting arm and bent downwardly to 30 form a stirrup depending from the arm at a point intermediate the length thereof and adapted to receive and support a brake rod.

7. A safety device for car trucks comprising a bracket having a vertical portion adapted to bear 35 against the adjacent wall of the upstanding flange of a spring board and provided with a terminal hook fitting over the upper portion of said flange, a horizontally disposed brake beam supporting arm extending laterally from the vertical portion 40 of the bracket and provided with a longitudinal reinforcing rib defining side flanges, said flanges being formed with incisions and the material at the end of the arm and at said incisions being bent downwardly to form a rod supporting stirrup 45 extending at substantially right angles to the arm and projecting therefrom at a point substantially midway between the ends of the arm.

8. A safety device for car trucks comprising an integral bracket stamped from a single sheet of 50 metal, one end of which is bent to form an upstanding portion terminating in a depending hook for engagement with the flange of a spring board, the intermediate portion of the metal sheet being pressed laterally to form a horizontally disposed 55 brake beam supporting arm and the metal at the end of said arm and at the sides thereof being cut and pressed downwardly at a point intermediate the length of the arm to form a rod supporting stirrup.

60 9. A safety device for car trucks comprising an integral bracket stamped from a single sheet of metal, one end of which is provided with an upstanding portion terminating in a depending relatively short hook adapted to fit over the upper 65 end of the flange of a spring board, the metal at the lower end of the upstanding portion of the bracket being bent laterally to form a horizontally disposed brake beam supporting arm having a longitudinal reinforcing rib extending the entire 70 length thereof and provided with a diagonal portion merging into and integral with the upstanding portion of the bracket, said reinforcing rib defining side flanges having portions thereof provided with incisions and the metal between the 75

incisions pressed downwardly at a point intermediate the length of the arm to form a depending stirrup for the reception of a bottom rod, there being spaced openings formed in the upstanding portion of the bracket beneath the bill of the hook for the reception of fastening devices.

10. A safety device for car trucks comprising a bracket having a vertical arm adapted for attachment to a spring board and a brake beam

supporting arm extending horizontally from the vertical arm, said horizontal arm being wide for a portion of its length from its inner end and having a narrow outer portion, and a rod supporting stirrup extending downwardly from the front end of the wide inner portion and united to opposite side portions thereof.
